CLAIM

The ornamental design for a flashlight, as shown and described.

DESCRIPTION

FIG. 1 is a perspective view according to a first embodiment of a flashlight showing our new design;

FIG. 2 is a front elevational view according to a first embodiment;

FIG. 3 is a rear elevational view according to a first embodiment;

FIG. 4 is a top plan view according to a first embodiment; FIG. 5 is a bottom plan view according to a first embodiment;

FIG. 6 is a left side elevational view according to a first embodiment;

FIG. 7 is a right side elevational view according to a first embodiment;

In the first embodiment of FIGS. 1-7, the battery shown in dashed line represents environment and does not form part of the invention;

FIG. 8 is a left side elevational view of a second embodiment of a flashlight with pivoting head showing our new design; FIG. 9 is a rear elevational view according to a second embodiment; and,

In the second embodiment of FIGS. 8-9, the battery forms part of the invention.

FIG. 10 is a left side elevational view similar to the view shown in FIG. 8 but showing an alternate orientation of the head in which the head is pivoted 90° from the position shown in FIG. 8.
